CENTERING DEVICE FOR SHOE SOLES

Filed Jan. 25, 1929

UNITED STATES PATENT OFFICE

JOHN A. PARKER, OF ST. LOUIS, MISSOURI, ASSIGNOR TO INTERNATIONAL SHOE COMPANY, OF ST. LOUIS, MISSOURI, A CORPORATION OF DELAWARE

CENTERING DEVICE FOR SHOE SOLES

Application filed January 25, 1929. Serial No. 335,000.

This invention relates to devices for centering shoe soles on the shoes to which the soles are to be attached and has special reference to a device of the character and for the purpose mentioned by use of which the soles will be located properly upon the shoes preparatory for attachment of the heel seats of the soles to the shoes.

An object of the invention is to provide a device of the character and for the purpose mentioned comprising a pair of pivotally mounted jaws having their adjacent edges shaped and formed in substantial conformity with the side edges of the shoe sole for which the device is intended, and a movable support for the last on which the shoe is mounted operative to move the toe portion of the shoe and the sole thereon between said jaws which are controlled effectively to center the sole on the shoe.

Another object of the invention is to provide a device of the character and for the purpose last mentioned which will rigidly support the last and the shoe thereon during the operation of tacking the heel seat of the sole to the shoe while the sole is held in centered position upon the shoe by said jaws.

Other objects will appear from the following description, reference being made to the accompanying drawing in which

Fig. 1 is a plan view of my improved sole centering device having a shoe mounted on the support and the shoe sole mounted on the shoe and centered on the shoe by said device.

Fig. 2 is a side elevation showing also the heel that is to be attached to the shoe.

Fig. 3 is a cross sectional view on the line 3—3 of Fig. 2.

In the embodiment of the invention shown the base 1 has a pair of vertical rods 2 in rigid connection with one end thereof. The upper ends of these rods may be threaded as shown and equipped with supports 3 in the form of nuts screwed on the threaded ends of said rods. A jaw 4 is pivoted on the upper end of each rod 2, said jaws being supported by the supports 3 for swinging movements toward and from each other. The adjacent sides of the jaws 4 are shaped to conform

substantially to the sides of the toe portions of the shoes for which the device is intended so that when the toe portion of a shoe is inserted between said jaws the adjacent surfaces of the jaws will approximately match the sides of the toe portion of the shoe and the sole (Fig. 1). These jaws are connected on their lower sides by a spring 5, the power of which is exerted to draw the jaws toward each other but which will yield to permit the jaws to be spread apart when the toe portion of the shoe is inserted between the jaws. The rear inner edge of each jaw 4 is formed with a beveled wall 6 so that when the device is idle and the jaws are held together by the spring 5 the diverging walls 6 will permit the toe portion of the shoe to be pressed between the jaws so as to separate the jaws, as shown in Fig. 1.

A support 7 is mounted for sliding movements on the base 1 between a pair of guides 8 which permit sliding movements of the support 7 toward and away from the rods 2. The support 7 has laterally extended tongues 9 engaging in correspondingly shaped grooves in the guides 8 to prevent displacement of the support 7 and to permit free movement thereof along the base 1 toward and away from the rods 2.

A rod 10 has its lower end rigidly attached to the support 7. The upper end of the rod 10 comprises a portion 11 extending angularly in a direction away from the rods 2 and terminating in a reduced portion 12 which is designed and adapted to be engaged in a correspondingly shaped hole in a shoe last 13. The height of the rod 10 relative to the positions in which the jaws 4 are supported is such that when a shoe last 13 is mounted on the rod 10 with a shoe on the last the toe portion of the shoe will be supported in a position for movement between the jaws 4. Thus when the shoe is on the last and the last is on the rod 10 and the sole is supported upon the shoe the support 7 may be moved toward the rods 2 to a sufficient extent to press the toe portion of the shoe and the sole between the jaws 4. Since the jaws 4 are drawn toward each other by the spring 5 it is apparent that said jaws will function to center the sole

upon the shoe. That will prevent the sole from being projected beyond the shoe or the shoe from being projected from beyond the sole when both are held and moved with equal pressure. Thus the jaws 4 will center the shoe sole on the shoe both as to its longitudinal and lateral positions.

The heel seat portion 14 of the sole 15 may then be attached to the shoe by tacks 16 which 10 will hold the sole on the shoe until the remaining portion of the sole can be attached by stitches 17.

The sole shown in the accompanying drawing may be recognized as a sole made in accordance with the invention disclosed in my 15 companion application Serial No. 335,002, filed Jan. 25, 1929 and including a tongue 18 for attachment to the breast wall of the heel and a transverse tongue 19 forming an abutment to engage against the front end of the heel to facilitate and expedite the attachment of the heel to the shoe. However, it is plain enough that the utility of the present invention is not restricted to the centering of any 25 specific types of soles but is capable of a wider range of use.

I am aware that the construction and arrangement of the device may be varied within equivalent limits without departure from the 20 nature and principle thereof. I do not restrict myself unessentially, but what I claim and desire to secure by Letters Patent is:—

1. A device of the character described comprising a pair of jaws pivotally supported 35 for movement toward and away from each other, means actuating said jaws toward each other, and a support for a lasted shoe for supporting the shoe in position for movement of the toe portion of the shoe and a sole on the shoe between said jaws and in a direction at right angles to the plane passing through the axes of the pivots of said jaws.

2. A device of the character described comprising a pair of pivotally supported jaws having their adjacent surfaces shaped to conform approximately to the sides of the toe portion of a shoe and a sole, a device actuating said jaws toward each other, and a device for supporting a lasted shoe and for moving the shoe in a direction at right angles to the plane passing through the axes of the pivots of said jaws and to a position in which the toe portion of the shoe and the sole thereon is between said jaws and in contact with the walls of said jaws.

3. A device of the character described comprising a pair of rigid upright rods, a jaw pivoted to the upper end of each of said rods, said jaws having their adjacent surfaces shaped to conform to and fit against the sides of a toe portion of a shoe and a sole, a spring for actuating said jaws to press said walls against the sides of a shoe and a sole inserted between said jaws, and a device for supporting a lasted shoe for movement at right angles

to the plane passing through the axes of said rods and to a position in which the toe portion thereof is between said jaws as aforesaid.

4. A device of the character described comprising a pair of rigid upright rods, a jaw pivoted to the upper end of each of said rods, said jaws having their adjacent surfaces shaped to conform to and fit against the sides of a toe portion of a shoe and a sole, a spring for actuating said jaws to press said walls against the sides of a shoe and a sole inserted between said jaws, a device for supporting a lasted shoe in position in which the toe portion thereof is between said jaws as aforesaid, and means for moving said device in a direction at right angles to the plane passing through the axes of said rods and to a position in which the toe portion of the lasted shoe on said device and the toe portion of the sole on said shoe are between and in contact with said walls of said jaws.

5. A device of the character described comprising a pair of pivotally supported jaws having their adjacent walls shaped to fit against the sides of the toe portion of a shoe and a sole projecting between said jaws, and a device for supporting and moving a lasted shoe at right angles to the plane passing through the axes of the pivots of said jaws to insert the toe portion of the shoe between said jaws.

6. A device of the character described comprising a pair of pivotally supported jaws having their adjacent walls shaped to fit against the sides of the toe portion of a shoe and the toe portion of a sole on the shoe, and having beveled walls at their ends, a spring for drawing said jaws toward each other, and means for supporting a lasted shoe and moving the lasted shoe in a direction at right angles to the plane passing through the axes of the pivots of said jaws and to an extent to move the toe portion of a shoe between said beveled walls and between the adjacent walls of said jaws to position in which said adjacent walls of said jaws contact with the sides of the toe portion of the shoe and the sides of a toe portion of a sole on the shoe.

7. A device of the character described comprising a pair of pivotally supported jaws having their adjacent walls shaped to fit against the sides of the toe portion of a shoe and the toe portion of a sole on the shoe, and having beveled walls at their ends, a spring for drawing said jaws toward each other, and means for supporting a lasted shoe and moving the lasted shoe in a direction at right angles to the plane passing through the axes of the pivots of said jaws and to an extent to move the toe portion of a shoe between said beveled walls and between the adjacent walls of said jaws to position in which said adjacent walls of said jaws contact with the sides of the toe portion of the shoe.

shoe and the sides of a toe portion of a sole on the shoe, said jaws centering the sole longitudinally and laterally on the shoe.

8. A device of the character described comprising a pair of vertical rods, a jaw pivoted to the upper end of each of said rods, said jaws having their adjacent walls shaped to fit against the sides of the toe portion of a shoe and a sole on the shoe, a movable support, means for guiding said support for movement toward and away from said rods, an upright rod rigid on said support, and means on the upper end of said upright rod for supporting a lasted shoe in a position in which the toe portion of the shoe and a sole on the shoe will be moved between said walls of said jaws when said support is moved toward said rods.
